UNITED STATES PATENT OFFICE.

WILLIAM M. PERKINS, OF NORTH MANCHESTER, INDIANA.

SAFETY CEMENT RAILROAD-TIE.

1,156,095.

Specification of Letters Patent.

Patented Oct. 12, 1915.

Application filed February 8, 1915. Serial No. 6,869.

To all whom it may concern:

Be it known that I, WILLIAM M. PERKINS, a citizen of the United States, residing at North Manchester, in the county of Wabash 5 and State of Indiana, have invented certain new and useful Improvements in Safety Cement Railroad-Ties; and I do hereby declare the following to be a full, clear, and exact description of the invention, such as 10 will enable others skilled in the art to which it appertains to make and use the same.

This invention relates to railroad ties and in particular to composite railroad ties of a compound form.

One of the objects of this invention is to provide a tie adapted to give under pressure yet rebound to a normal position after the load has been lifted.

Another object of this invention is to provide an arrangement which is flexible in its transverse direction but rigidly keyed against longitudinal strain.

Another object of this invention is to provide an arrangement which is firmly keyed 25 to its bed.

Another object of this invention is to provide a composite tie provided with longitudinal reinforcing elements, said elements adapted to lock the rail to the tie.

Other objects and advantages of this invention will be hereinafter more clearly set forth in the specification and pointed out in the claims.

Similar characters of reference refer to 35 similar parts throughout the specifications and claims, in which,

Figure 1 is a top plan view of this device in assembled formation. Fig. 2, is a sectional elevation of the same, and, Fig. 3 40 is a sectional elevation of a portion of the tie showing a modified form of means for clamping the rail to the tie.

In the drawings, the tie is composed of like members 1 and 2 preferably formed 45 of concrete, each of said members having a longitudinal recess 3 in the top portion thereof and a longitudinal recess in the lower portion thereof in which are mounted metallic bands or plates 4 and 5, said plates 50 being integral their full length of the upper portion of the tie members and being seated in the groove 3 and extending beyond the inner ends 6 and 7 of the tie members and looped back and seated in the longitudinal recesses in the under portion of the tie members. A plurality of vertically positioned

apertures 8 are formed in each of the tie members through each of which is mounted a suitable sleeve 9, the metallic bands 4 and 5 having apertures adapted to register with 60 the apertures through the tie members. Locking means 10 are mounted through these apertures, a portion of which are adapted to clamp a rail 11 of ordinary construction and the resilient bed plate 12 65 thereof to the tie to prevent lateral movement of said rails, said fastening means 10 having threaded ends 13 seating the locking nuts 14 for this purpose. Between the looped ends of each of the bands 4 and 5 70 and the ends 6 and 7 of each of the tie members are mounted metallic structures 15 and 16 as shown in Fig. 2, said structures and bands 4 and 5 being preferably curved on their lower faces so that the major portion of the tie will be directed on the centers of each section. A vertically disposed aperture 17 is formed in each of these metallic members through which is mounted a locking bolt 10 held in position by the nut 14. 75 A pair of oppositely disposed link members 18 and 19 are placed upon the sides of these metallic members and locked into position by means of transverse bolts 20 to allow of flexible play between the tie members 1 80 and 2, a plurality of openings for said bolts 20 being provided in one of the metallic members to allow of longitudinal adjustments of the tie sections. A second transverse bolt 21 is mounted through one of the 85 metallic structures and through said link members 18 and 19 for the purpose of keeping said link members in true parallel alignment with one of said tie members, the other member being allowed to play. It is to be 90 further noted that the heads 22 of the bolts are below the under surface of the tie members and are adapted to project into the bed or earth to securely anchor said tie members in place.

In the modified form shown in Fig. 3 the same tie constructions are used as illustrated above, the members 1 and 2 having the bands 4 and 5 therearound, the rail 11 and the bed plate 12, but in this instance the resilient base plate 12 is wider than the base flanges of the rail 11, said base flanges and said base plate having registering apertures 105 therethrough. Anchoring plates 23 and 24 are oppositely disposed above the base flanges of 110 the rail, the ends of which abut against the web of said rail, said plates extending to a

neighboring locking bolt 10, said anchoring plates 23 and 24 having suitable apertures therethrough to engage the locking bolts 10 which are mounted through the said registering apertures, so that when the nuts 14 are threaded home, said anchoring plates 23 and 24 will securely bind the rail in position and prevent lateral displacement of the rail, the strain of said displacement being taken up by the neighboring locking bolts 10. Suitable angular washers 25 are placed between the flanged ends of the anchoring plates 23 and 24 and the nut 14 to prevent distortion of the locking bolts 10. By this arrangement when the load of passing cars is delivered to the ties, each portion thereof will properly give, thereby allowing of a resilient action of the rail 11, yet preventing lateral displacement of said rails, said ties returning to their normal position after the load is released from off said ties, and likewise by means of the bands 4 and 5 and the locking bolts 10, the strain of this displacement is distributed to all points of said tie thereby insuring a strong and durable arrangement.

Having now described my invention what I claim as new and desire to secure by Letters Patent, is:

- 30 1. A composite railroad tie, comprising oppositely disposed members, metallic loop members reinforcing said oppositely disposed members, a metallic structure mounted in the looped portion of each of said metallic means, and pivoted connecting means, connecting said oppositely disposed members, and pivoted through said metallic structures to allow of resilient play of said members.
- 35 2. A composite railroad tie composed of oppositely disposed concrete members having transverse vertically disposed apertures therein, sleeves mounted in said apertures, a looped metallic band above and below each 45 of said concrete members, said bands having

apertures registering with the apertures in said concrete members, reinforcing fastening means passed through said sleeves and locking, said metallic bands and linking means pivoted in the loop portion of said bands to allow of resilient play of each of said concrete members.

3. A composite tie comprising oppositely disposed concrete members having longitudinal recesses in the top and bottom portions, a metallic looped band, seated in said recesses the loop portions thereof extending beyond the inner ends of said concrete members, metallic structures mounted in said looped portions, pivoted connecting means mounted through said metallic structures and connecting said concrete members, transverse locking reinforcing elements mounted through said concrete members and said metallic bands to reinforce and lock the same in position, a rail plate, a rail mounted upon said rail plate, and means locking said rail to a portion of said transverse locking means.

4. A composite tie comprising oppositely disposed members, loop reinforcing members, metallic members in said loop members, pivoted linking means mounted on said metallic members and abutting said loop portions, a rail plate mounted upon each of said oppositely disposed members, a rail mounted upon said rail plates, and bolt means passing through said loop members and said oppositely disposed members, a portion of which operate to fasten said rails, the lower ends of said reinforcing means operating to anchor said tie to its bed to prevent displacement therefrom.

In testimony whereof I have signed my name to this specification in the presence of two subscribing witnesses.

WILLIAM M. PERKINS.
